BY *Nietor J. Evans*

WITNESS:

UNITED STATES PATENT OFFICE.

MYER SIEGEL, OF BRONX, NEW YORK.

AUTOMATIC PICOT CUTTER FOR HEMSTITCHING MACHINES.

Application filed June 10, 1925. Serial No. 36,258.

This invention relates to improvements in automatic picot cutters for hemstitching machines.

The principal object of the invention resides in a cutter positioned rearwardly of the piercer bar of a hemstitching machine for automatically severing the threads of the fabric worked upon for producing a picot edge, the cutter being operated by the movement of the piercer plunger bar.

Another object of the invention is to provide a lateral adjusting means for the cutting blades so as to position them at all times in alignment with the piercer bar for assuring an even picot edge on both edges of the fabric formed by severing the same.

A further object is the provision of a pair of cutting blades pivotally mounted upon the pressed foot of a hemstitching machine, and tension means for holding said blades in cutting relation and for automatically compensating for any wear between said blades.

A still further object is to provide a cutter composed of a pair of pivoted blades for attachment to the presser foot of a hemstitching machine for automatically cutting the goods passed through the machine for forming a picot edge, and means for rendering the cutting blades inoperative when desired to use the machine for hemstitching only.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a side elevation of my invention as applied to the presser foot of a hemstitching machine, the cutting blades being shown in an operative position.

Figure 2 is an end elevation.

Figure 3 is a horizontal sectional view on the line 3—3 of Figure 1.

Figure 4 is a horizontal sectional view on the line 4—4 of Figure 1.

Figure 5 is a detail view of the cutting blades in an inoperative position.

Referring more particularly to the drawing, the reference numeral 10 designates the presser foot bar of a hemstitching machine and which supports the presser foot 11 which in turn is provided with spaced shoes 12.

Positioned forward of the presser foot bar 55 is a plunger rod 13 which is adapted to be reciprocated by the usual mechanism, and which rod supports a piercer bar bracket 14 which carries the usual piercer 15 which moves between the shoes 12 of the presser 60 foot. The structure thus far described is all very old in the art but it is to these parts of the machine to which my invention is adapted to be attached. My improved cutting device includes a block 16 fixed to the presser 65 foot rearward of the same and which block is provided with a bifurcation 17. The furcations 18 formed by the bifurcation 17 are provided with aligned threaded openings 19, which receive externally threaded sleeves 20 70 and 21. The bores of the sleeves receive a shaft 22 and which shaft supports a pair of cutting blades 23 and 24. The sleeve 21 abuts the blade 24, while a collar 25 keyed to the shaft 22 abuts the blade 23 and a 75 spring 26 encircles the shaft 22 and is interposed between the collar 25 and the end of the sleeve 20. It will therefore be seen that the blades may be moved laterally within the bifurcation by the manipulation of the 80 sleeve 21, and the tension between the blades may be regulated by the operation of the sleeve 20. The tension means provided by the spring will automatically "take-up" any wear between the cutting blades and should 85 the blades become out of alignment with the plunger piercer 15, the same may be readily adjusted by the operation of the sleeve 21. For the purpose of locking the sleeves 20 and 21 in adjusted position, I provide suitable 90 lock nuts 27 threaded to the sleeves and which are adapted to abut the sides of the block 16.

The blade 23 above referred to is adapted to be positioned when in operative position 95 upon the platform over which the goods to be cut is moved, and which shall be termed the stationary blade as the same does not operate after being moved to an operative position. The blade 24 is so positioned that the same does not touch the platform during the operation of the same and this blade will be termed the movable blade as the same is operated during the reciprocation of the piercer bar when the blades are in operative 100 position.

The stationary blade 23 has its free end connected with a spring 28 and which spring

is connected to a collar 29 carried by the presser foot bar 10. The action of the spring is to hold the cutting end of the blade in an operative position for co-action with the movable blade.

The means for operating the movable blade comprises a link 30 pivoted to the piercer bar bracket 14 and which link is connected with a connecting rod 31. A crank 32 is journaled in the block 16, and to one end of which the connecting rod 31 is secured. A link 33 connects the other end of the crank with the tail of the movable blade 24. From this construction, it will be noted that the connecting rod 31 and crank 32 serve as a rocker arm for imparting movement from the piercer bar 13 during its reciprocating movement to the movable blade, which blade co-acts with the stationary blade to sever a fabric between the holes left therein by the piercer bar and which provides a picot edge on the fabric after being severed, as the edges are bound by stitching provided by the usual needles of the hemstitching machine. The crank 32 is radially adjustable with respect to the link 31 by means of a set screw 39 so as to take up the wear of the movable blade.

When the machine is adapted for use for hemstitching purposes only, the stationary blade which is normally disposed adjacent the platform, may be moved to an inoperative position by a suitable means now to be described. A split bearing 34 is formed in the rear face of the block 16 and supports a shaft 35, which has keyed thereto a finger 36 which is disposed in the path of the tail of the stationary blade 23. A set screw 37 passes through the bearing and coacts with the shaft for holding the same in an adjusted position against the action of the spring 28 when the finger is moved to a position for holding the cutting end of the blade above the platform. A manipulating handle 38 is also keyed to the shaft for permitting the shaft to be rotated for moving the finger to an operative and inoperative position. When the finger is engaged with the tail of the stationary blade, the same will hold the blade in an elevated position against the tension of the spring 28 which will permit the fabric worked upon to pass beneath the cutter blades without contacting therewith.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

65 1. In an automatic picot cutting device,

the combination with the presser foot and piercer bar of a hemstitching machine, a pair of cutting blades, means between said piercer bar and one of said blades for imparting movement from the former to the latter, and adjusting means for laterally moving said cutting blades, said last means including a pair of aligned sleeves adjustably supported by said presser foot, one of said sleeves engaging one of said blades, a shaft supported by said sleeves and on which said blades are pivotally mounted, and a spring interposed between the other of said sleeves and the other of said blades.

2. In an automatic picot cutting device, the combination with the presser foot and piercer bar of a hemstitching machine, said presser foot having a bifurcation therein, a pair of sleeves adjustably mounted in the furcations formed by said bifurcation at diametrically opposite points, a shaft supported by said sleeves, a pair of cutting blades mounted on said shaft, tension means for holding said cutting blades in co-acting position against one of said sleeves, and means for transmitting motion from said piercer bar to one of said cutter blades.

3. In an automatic picot cutting device, the combination with the presser foot and piercer bar of a hemstitching machine, said presser foot having a bifurcation therein, a pair of sleeves adjustably mounted in the furcations formed by said bifurcation at diametrically opposite points, a shaft supported by said sleeves, a pair of cutting blades mounted on said shaft, tension means for holding said cutting blades in co-acting position against one of said sleeves, means for transmitting motion from said piercer bar to one of said cutter blades, and means engageable with the other of said cutter blades for holding the same in an inoperative position.

4. In an automatic picot cutting device, the combination with the presser foot and piercer bar of a hemstitching machine, said presser foot having a bifurcation therein, a pair of sleeves adjustably mounted in the furcations formed by said bifurcation at diametrically opposite points, a shaft supported by said sleeves, a pair of cutting blades mounted on said shaft, tension means for holding said cutting blades in co-acting position against one of said sleeves, and means for transmitting motion from said piercer bar to one of said cutter blades.

5. In an automatic picot cutting device, the combination with the presser foot and piercer bar of a hemstitching machine, said presser foot having a bifurcation therein, a pair of sleeves adjustably mounted in the furcations formed by said bifurcation at diametrically opposite points, a shaft supported by said sleeves, a pair of cutting blades mounted on said shaft, tension means

for holding said cutting blades in co-acting position against one of said sleeves, and means for transmitting motion from said piercer bar to one of said cutter blades, said last means including a crank shaft operatively connected with said piercer bar and one of said cutting blades by suitable links,

and means for radially adjusting the crank shaft with relation to the link connecting the same with said piercer bar. 10

In testimony whereof I have affixed my signature.

MYER SIEGEL.
